FUEL INJECTION PUMP

William Friedlander, Westminster, London, England, assignor to Mono-Cam Limited, Westminster, London, England, a company of Great Britain

Application June 4, 1951, Serial No. 229,792

Claims priority, application Great Britain
June 6, 1950

4 Claims. (Cl. 103—2)

1

This invention relates to fuel injection pumps for internal combustion engines, particularly though not exclusively, compression-ignition engines. It is concerned with improvements in pumps of the kind (hereinafter referred to as "the kind specified") in which the effective length of the delivery strokes of the respective pistons is similarly controlled simultaneously for all the pump cylinders by actuation of a common regulating member which adjusts, for each cylinder, the position of an element which determines at what point in the delivery stroke fuel will be spilled from the cylinder into a chamber or passage in communication with the inlet side of the pump, the fuel tank or a like low-pressure region, the common regulating member being a plate or disc and the elements adjusted thereby being sleeves fitted over the pump pistons or plungers to control the outlet ends of spill passages which run through the pistons or plungers from the operative end faces thereof to the cylindrical surfaces thereof.

In such pumps it is desirable, from the point of view of ease of manufacture, that the sleeves shall be positioned transversely of their axes solely by their engagement with the pump pistons or plungers while it is essential that there shall be no appreciable axial motion of the sleeves relative to the common regulating member once they have been adjusted correctly in relation thereto.

A pump of the kind referred to is described in the specification of Letters Patent No. 2,517,483 and the means for mounting the sleeves in the common regulating member which is there employed affords these desirable and essential features but is somewhat expensive to manufacture and requires careful adjustment by relatively skilled operatives.

The object of the present invention is to provide an improved and simpler arrangement whereby these disadvantages may be avoided.

According to the invention, in a fuel injection pump of the kind specified, the sleeves are located in the common regulating member so that they are all positioned axially in relation thereto by two common opposed axially spaced surfaces provided on the member while being free to adjust themselves transversely of their axes by sliding between these surfaces.

It is preferred to construct the regulating member with two parts each affording one of the surfaces and adapted to be secured together with the interposition of spacing elements, one of the parts having a number of apertures each arranged to accommodate one of the sleeves with radial clearance and each sleeve having a flange of larger transverse dimensions than the corresponding aperture and adapted to be engaged

2

between the operative positioning surfaces of the parts of the member. The axial dimension of the flange on a sleeve is made shorter than or equal to the axial dimension of a spacing element so that the flange will not be gripped between the positioning surfaces when the parts are secured together. The difference in these dimensions may be very small, so that the flange is merely slidable between the surfaces, or may be somewhat larger, so that shims may be interposed between the flange and one or both of the positioning surfaces to afford a range of axial adjustment to the sleeve while still ensuring that it can only slide between the surfaces of the shims without moving axially relative to the regulating member. By the last-mentioned arrangement provision may be made for effecting axial adjustments of the several sleeves to different degrees.

In order that the invention may be clearly understood, an example of the way in which it may be carried into effect will now be described in greater detail with reference to the accompanying drawings.

In this example, the pump chosen for illustrative purposes is constructed substantially in accordance with the invention forming the subject matter of Letters Patent No. 2,517,483 but the present invention may be applied also to other constructions of pumps of the kind specified above without difficulty.

In the drawings:

Fig. 1A is an upper part of a section taken on the line I—I of Fig. 3 a part being broken away,

Fig. 1B is the lower part of this section,

Fig. 2 is a fragmentary sectional view taken on the line I—I of Fig. 3 showing the regulating member of Fig. 1A and illustrating a modification employing shims, and

Fig. 3 is an under plan view of Fig. 2 but with the shims omitted.

The pump, as shown in Fig. 1A, comprises a generally cylindrical housing 1 having a cam chamber 2 (Fig. 1B) at one end, a spill chamber 3 intermediate its length and a series of delivery connections 4 at its other end which are each connected to the fuel injection device of the respective engine cylinder. At this end of the housing there are the appropriate pump cylinders 5 disposed around and parallel with the axis of the housing and each communicating through a delivery valve 6 with the corresponding delivery connection 4. The cylinders 5 and the respective pistons or plungers 7 are all identical and only one set of these parts need be described here. The cylinder wall is formed with radial bores 8 near its outer end and is surrounded at this location by an annular fuel supply passage 9. This is in permanent communication with a central

annular chamber 10 (supplied from an inlet not shown) formed by a recess in the cylindrical wall 12 of the enlarged inner end 11 of an axial bore 12 in the housing 1 provided to admit the passage of a stem 13 attached to a common regulating member 14, 15, 16, located in the spill chamber 3. The regulating member serves to position controlling sleeves 17 which are a close sliding fit on the pistons 7 working in the cylinders 5. Each piston 7 is a close sliding fit in its cylinder 5 which projects, with play, part-way into an aperture 18 in the regulating member, the corresponding controlling sleeve being mounted on the latter in such manner that it may move laterally (e. g. radially or circumferentially of the member) 15 without being capable of any appreciable motion relative to the member in the axial direction.

The piston 7 continues beyond the sleeve 17, through an over-size hole 19 in a partition member 20 secured transversely of the spill chamber 3, to be surrounded by a compression spring 21 bearing at its ends upon the partition member 20 and upon a collar 22 secured on the end of the piston, respectively. This end of the piston 7 bears upon one end of a reciprocable push rod 23 the other end of which (see Fig. 1B) carries a roller 24 co-operating with a face cam 25 rotatable within the cam member 2 by means of a shaft 26 extending axially through the end of the housing 1 to be driven from the engine crank-shaft at an appropriate speed.

Centrally of the partition member 20 (see Fig. 1A) is formed an axially extending cylindrical wall 27 surrounding a liner 28 within which slides a spigot part 29 secured on the regulating member 14. Axial adjustment of this member varies the position of the controlling sleeves 17 relative to the length of the pistons 7 which are formed with axial bores 30 leading from their operative end faces to radial bores 31 the opening of which occurs as they move out of the controlling sleeves 17 during the delivery strokes of the respective pistons.

The pump thus far described operates in exactly the same manner as that described in specification No. 2,517,488 rotation of the face cam 25 causing reciprocation of the pistons 7 and the consequent delivery, per working stroke, of a quantity of fuel determined by the spacing for the time being of the controlling sleeves 17 from the cylinders 5.

According to this invention the regulating member is made in two parts, one part constituting a disc-like element 14 formed with a thickened edge 15 and the other part being a ring 16 of the same or substantially the same external diameter as the first part. The ring 16 is clamped to the thickened edge 15 of the disc-like element 14 and has apertures 32 formed therein, each aperture being traversed by the corresponding plunger 7 of a diameter somewhat larger than that of the main body of the sleeve 17 which is slidably fitted on that plunger. Each sleeve 17 has a flange 33 at its one end which is larger in diameter than the respective aperture 32 and all the sleeve flanges 33 are made of the same axial thickness.

The ring part 16 of the regulating member is arranged to be attached to the disc part 14 by bolts 34 or the like with the interposition of spacers 35 of an axial length equal to or somewhat greater than the axial thickness of the sleeve flanges 33. See Fig. 1A for an example of the case where the spacers 35 are of an axial length equal to the axial thickness of the sleeve flanges 33 and Fig. 2 for an example of the case in which the

axial length of the spacers 35 is greater than the axial thickness of the sleeve flanges 33, shims being provided to prevent axial movement of the sleeves.

In the assembly of the parts, the disc 14 is first placed in position with the plungers 7 extending therethrough, the sleeves 17 are slid flange-first on to the respective plungers 7, and the ring 16 is threaded over the latter so that the main bodies of the sleeves 17 are accommodated in the apertures 32 in the ring 16. The latter is then secured to the disc 14, with the interposition of the spacers 35 and the distance between the adjacent surfaces of the ring 16 and thickened edge 15 of the disc 14 is then such in the case of Fig. 1A, that the flanges 33 of the sleeves 17, though capable of moving laterally between these surfaces, cannot move to any appreciable extent in the axial direction relative thereto.

In order that the required precision may be secured, the positioning surfaces of the ring 16 and disc 14 are preferably ground true, as are also the co-operating faces of the sleeve flanges 33 and of the spacers 35.

Where adjustment of one sleeve relative to another in the axial direction may be required, it is preferred to make the spacers 35 of an axial length greater than that of the sleeve flanges 33 (see Fig. 2) by an amount corresponding to the maximum adjustment that can be required. In this case, the excessive axial play that would otherwise be allowed to the sleeve flanges 33 between the positioning surfaces is taken up by the insertion of annular shims 36 between the respective faces of the flanges 33 and the positioning surfaces. These shims are individual to the respective sleeves so that by appropriately selecting their thicknesses, the several sleeves may be differently positioned axially with respect to the regulating member.

It will be appreciated that the manufacturing operations required for producing the several parts are of a simple character yet capable of performance with a high degree of precision. Further, the assembly and adjustment of these parts is a simple matter.

What I claim is:

1. A fuel injection pump comprising a pump housing, a plurality of pump piston and cylinder assemblies located within the housing with their axes parallel to each other, each piston being reciprocable in a cylinder, a cam for reciprocating the pistons, a spill passage in each piston, a spill chamber formed in the housing, an element slidably axially on each piston to determine by its axial position the point in the stroke of the piston at which the spill passage therein will be placed in communication with the spill chamber, a regulating member mounted within said spill chamber and displaceable in a direction parallel to said axes, a first abutment surface formed on said member to extend normal to said axes, a first locating surface associated with each of said elements and arranged to slidably engage said first abutment surface, a second abutment surface formed on said member and spaced from said first abutment surface in a direction parallel to said axes, and a second locating surface associated with each of said elements and arranged to slidably engage said second abutment surface, said first and second abutment surfaces engaging said first and second locating surfaces respectively to control said axial position of said elements whilst permitting the latter to adjust themselves in a direction normal to said axes by said first

and second locating surface sliding over said first and second abutment surfaces respectively.

2. A fuel injection pump comprising a pump housing, a plurality of pump piston and cylinder assemblies located within said housing with their axes parallel to each other, each piston being reciprocable within a cylinder, a cam for reciprocating said pistons, a spill passage in each piston, a spill chamber formed in the housing, an element slidable axially on each piston to determine by its axial position the point in the stroke of the piston at which the spill passage therein will be placed in communication with the spill chamber, a first part mounted within said spill chamber and displaceable in a direction parallel to said axes, a first abutment surface formed on said first part and arranged to extend normal to said axes, a second part mounted within said spill chamber and displaceable in a direction parallel to said axes, a second abutment surface formed on said second part and arranged to extend normal to said axes, spacing means interposed between said first and second abutment surfaces to maintain these latter in spaced parallel relationship, means for securing said first and second parts and said spacing means together to constitute a regulating member, a first locating surface associated with each element and arranged to slidably engage said first abutment surface, a second locating surface associated with each element and arranged to slidably engage said second abutment surface, said elements being held against displacement relative to said member in a direction parallel to said axis by engagement of said first locating surface with said first abutment surface and said second locating surface with said second abutment surface respectively whilst being capable of adjusting themselves in a direction normal to said axis by said first locating surface sliding over said first abutment surface and said second locating surface sliding over said second abutment surface respectively.

3. A fuel injection pump comprising a pump housing, a plurality of pump and cylinder assemblies located within said housing with their axes parallel to each other, each piston being reciprocable within a cylinder, a cam for reciprocating said pistons, a spill passage in each piston, a spill chamber formed in said housing, a sleeve element slidable axially on each piston to determine by its axial position the point in the stroke of the piston at which the spill passage therein will be placed in communication with the spill chamber, a first part mounted within said spill chamber and displaceable in a direction parallel to said axes, said first part being formed with a number of apertures each arranged to accommodate one of said sleeve elements with clearance, a flange formed on each of said elements of larger transverse dimensions than the corresponding aperture, and a second part mounted in said spill chamber and displaceable in a direction parallel to said axes, a first abutment surface formed on said first part to extend normal to said axes, a second abutment surface formed on said second part to extend parallel to said first abutment surface, spacing means interposed between said first and second abutment surfaces to maintain these latter in spaced parallel relationship, means for securing said first and second parts and said spacing means together to constitute a regulating member, a first locating surface formed on said flange and arranged to slidably engage said first abutment surface, a second locating surface formed on said flange parallel to said first locating surface, said first and second locating surfaces being spaced apart in a direction parallel to said axes by a distance not greater than the height of said spacing means in the same direction, said sleeve elements being held against displacement relative to said member in a direction parallel to said axes by engagement of said first locating surface with said first abutment surface and said second locating surface with said second abutment surface respectively.

first abutment surface, a second locating surface formed on said flange and arranged to slidably engage said second abutment surface, said sleeve elements being held against displacement relative to said member in a direction parallel to said axes by engagement of said first locating surface with said first abutment surface and said second locating surface with said second abutment surface respectively whilst being capable of adjusting themselves in a direction normal to said axes by said first locating surface sliding over said first abutment surface and said second locating surface sliding over said second abutment surface respectively.

4. A fuel injection pump comprising a pump housing, a plurality of pump piston and cylinder assemblies located within said housing with their axes parallel to each other, each piston being reciprocable within a cylinder, a cam for reciprocating said pistons, a spill passage in each piston, a spill chamber formed in said housing, a sleeve element slidable axially on each piston to determine by its axial position the point in the stroke of the piston at which the spill passage therein will be placed in communication with the spill chamber, a first part mounted within said spill chamber and displaceable in a direction parallel to said axes, said first part being formed with a number of apertures each arranged to accommodate one of said sleeve elements with clearance, a flange formed on each of said elements of larger transverse dimensions than the corresponding aperture, a second part mounted in said spill chamber and displaceable in a direction parallel to said axes, a first abutment surface formed on said first part to extend normal to said axes, a second abutment surface formed on said second part to extend parallel to said first abutment surface, spacing means interposed between said first and second abutment surfaces to maintain these latter in spaced parallel relationship, means for securing said first and second parts and said spacing means together to constitute a regulating member, a first locating surface formed on said flange and arranged to slidably engage said first abutment surface, a second locating surface formed on said flange parallel to said first locating surface, said first and second locating surfaces being spaced apart in a direction parallel to said axes by a distance not greater than the height of said spacing means in the same direction, said sleeve elements being held against displacement relative to said member in a direction parallel to said axes by engagement of said first locating surface with said first abutment surface and said second locating surface with said second abutment surface respectively whilst being capable of adjusting themselves in a direction normal to said axes by said first locating surface sliding over said first abutment surface and said second locating surface sliding over said second abutment surface respectively.

WILLIAM FRIEDLANDER.
